HULL

Application filed February 3, 1928. Serial No. 251,703.

The present invention relates to the hulls of ships, boats or other like craft, the object of the invention being to provide a design whereby resistance to motion is reduced to a minimum and thus high speeds can be obtained with economy in the propulsion expenses.

According to the invention the water-line plan of the hull extends from the stem to the stern and the maximum beam dimension is above the water-line, whilst the maximum beam section is situated pronouncedly nearer the bow than the stern and the shell tapers from this point towards the stern whereby the midship and the centre of gravity line are, as compared with a normal hull, much nearer the bow.

Hulls have previously been proposed, in which the water-line plan extends from the stem to the stern, whilst the maximum beam section is situated nearer the bow than the stern and the shell tapers towards the stern. Here, however, the maximum beam dimension is below the water-line. Hulls have also been proposed with a tapering submerged part, but here the keel takes an upward curvature towards the front of the hull so that the stem is completely out of the water and the water-line plan therefore does not extend from stem to stern. Furthermore in this proposal the sides of the shell extend parallel over the greater part of the length. Again, hulls have been proposed in which the water-line plan extends substantially from the stern to the stem. In this case however the maximum beam section is nearer the stern than the bow and the maximum beam section is the same above the water-line.

The present invention is diagrammatically illustrated in the accompanying drawing in which:—

Figure 1 is a side elevation of the hull, Figure 2 a plan of one half of the hull, depicting plan-sections thereof on several of the horizontal lines shown in Figure 1,

Figure 3 is a cross-section on an enlarged scale, depicting the beam sections on several of the vertical lines 0 to 10 shown in Figure 1, and

Figure 4 is a diagrammatic plan illustrative

of the hydrodynamic pressures and forces involved during the motion and maneuvering of the vessel.

Referring to the drawing H indicated the hull, whilst WL indicated the water-line which as will be observed extends from the stem Sm to the stern Sn so that the whole of the keel K is submerged.

The maximum beam section, as indicated by the line 7 (Figures 1 and 3) and by the cross-section is situated much nearer the bow than the stern, being preferably larger than normally, whilst from this point the submerged portion at least of the shell tapers continuously and pronouncedly to the stern as shown more clearly in Figure 2. By this means the midship and the centre of gravity which is near to the same line 7 is much nearer the bow than in a hull of usual construction. In actual practice it is preferred that this line shall be situated at a distance from the bow of about $\frac{1}{3}$ to $\frac{1}{4}$ the total length of the hull.

The power unit for propelling the vessel is arranged as usual in the region of the centre of gravity. With a design of hull according to the present invention therefore, the power unit is comparatively near the bow, but nevertheless this arrangement does not detract from the practicability of the design but rather leads to advantages. Owing to the nearness of the power unit to the bow it is practical to have forwardly arranged propelling means because the propeller shaft or shafts need be but comparatively short which as is well recognized in the art is very desirable, not only from the point of view of efficiency but also because such arrangement avoids complications in maintaining alignment of the shaft or shafts and in taking account of the torque. The propelling means

may comprise a single screw or other mechanically operated propelling means centrally arranged beneath the bow or, a pair of screws arranged one on either side of the bow in combination with other mechanically operated propelling means. The provision of these forwardly arranged propelling screws increases the efficiency of propulsion because these screws are not disturbed to any

serious extent by eddy currents, but reduce to a minimum the currents created by the stern, the latter may be pronouncedly inclined as shown in Figure 1. Shaping the stern in this 5 way also has the tendency to direct the water downwards towards the screws, whilst it is preferred that the cross-sections in proximity to the screws shall be of lesser draft, as shown, that successive cross-sections, thus 10 permitting water to have full access to the screws which are also protected against breakage by collision.

It may be thought that the advantage mentioned above would be negatived in the case 15 of propulsion of the vessel from the rear owing to the increased distance of the power unit from the stern. This however is not so as owing to the pronounced tapering of the hull towards the stern it is possible to have 20 rear propelling means projecting from the sides of the hull at points comparatively near the midship section and close to the power unit whilst still maintaining the axes of the propeller shafts substantially parallel with 25 the longitudinal axis of the vessel which is necessary for efficiency. Such propelling means preferably comprises a pair of screws arranged one on either side of the keel (k).

The increase of the maximum beam section 30 above the normal renders it possible to install a larger power unit without occupying too much space longitudinally of the vessel. Furthermore this increase and this installation of the power unit gives a corresponding 35 large forecastle deck and a larger upper-bridge deck which is thus rendered eminent- ily suitable for the provision of landing and take-off gear for aircraft.

It will be observed from Figure 3 that the 40 maximum beam dimension of the hull is above the water line WL. In fact the greatest dimension on any cross-section is above the water line as generally indicated in this figure. In this respect therefore the improved 45 hull differs from those in which the greatest beam section is below the water-line.

Owing to the provision of a pronounced and continuous taper from the centre of gravity or from the midship section to the stern, eddy 50 currents towards the rear of the vessel are reduced to a minimum, so that the rear screws work in water which is practically undisturbed or at any rate is flowing only from front to rear and therefore these screws work 55 with increased efficiency in propelling the vessel. Furthermore the sides of the hull as shown in Figure 3 are made somewhat concave giving an additional tendency to direct the water downwards not only towards the 60 rear screws but also towards the front screws.

Preferably the upper decks which are indicated at 16 are given substantially the same shape in plan as the water-line plan of the hull as shown in Figure 2 thus reducing to a 65 minimum the retarding action of the air

above the water-line when the vessel is in motion.

The forward situation and comparatively wide construction of the midship section coupled with the rearward tapering of the hull 70 gives rise to hydrodynamic forces which also illustrate the efficiency of the construction. These forces are depicted in Figure 4.

Referring now to Figure 4, the hydrodynamical pressure on the hull, when in motion, 75 is represented by the line 13, which indicates that from the two resultants 14 of the elementary pressures a totally axial resultant 15 is obtained which is directed from stern to bow. This resultant indicates that the resistance to 80 motion of the hull through the water at the forward end of the vessel is partly compensated.

Further, account must be taken of the fact 85 that the reaction represented by the line 16' of the rudder 17 on the water has, with reference to the centre of gravity G of the hull a lever arm 18 which is bigger than would be the lever arm 19 should the centre of gravity be at a point G' situated midway between the 90 stern and the stern as occurs in vessels of ordinary construction. It should also be observed that the resultant 20 of the reactions of the water on the hull during movement has, with regard to the actual centre of gravity G, a lever arm 21 which is smaller than would be the lever arm 20' of the resultant should the centre of gravity be at G'. 95

Having now particularly described and ascertained the nature of my said invention 100 and in what manner the same is to be performed, I declare that what I claim is:

A hull, with the characteristics that the hull below the water with a maximum width 105 at about one-third to one-fifth of the length of vessel includes waterlines from the bow in the shape of a drop and changes at the fore part into a shape above the water which has the usual waterlines tapering towards the bow, the edge of the stem reaching below the surface of the water, bow screws and the stern screws, the latter being located as far as possible towards the longitudinal center, and the upper structures seen in horizontal 110 sectional view having a form of drop corresponding to the hull below the water line. 115

In testimony whereof I affix my signature.

LUIGI GHIRARDI.
